US00D889393S

(12) **United States Design Patent** (10) Patent No.: **US D889,393 S**
(45) Date of Patent: ** Jul. 7, 2020

(54) **SOLAR CELL**

(71) Applicant: **REC Solar Pte. Ltd.**, Singapore (SG)

(72) Inventors: **Kenta Nakayashiki**, Singapore (SG);
Bjoern Erik Andersson, Singapore (SG)

(73) Assignee: **REC Solar Pte. Ltd.**, Singapore (SG)

(**) Term: **15 Years**

(21) Appl. No.: **29/704,794**

(22) Filed: **Sep. 6, 2019**

(30) **Foreign Application Priority Data**

Mar. 8, 2019 (EM) 006297073

(57) **CLAIM**

The ornamental design for a solar cell, as shown and described.

DESCRIPTION

FIG. 1 is a top perspective view of a solar cell according to our new design;

FIG. 2 is a top view thereof;

FIG. 3 is a bottom view thereof;

FIG. 4 is a front view thereof;

FIG. 5 is a rear view thereof;

(Continued)

FIG. 6 is a right-side view thereof, the left side view being a mirror image; and,

FIG. 7 is an enlarged view of a portion of FIG. 1.

The broken lines in the drawings represent environmental subject matter and form no part of the claimed design.

1 Claim, 7 Drawing Sheets
